UNITED STATES PATENT OFFICE

RALPH SHIPMAN, OF SUNBURY, PENNSYLVANIA

CARBURETOR

Application filed July 1, 1927. Serial No. 202,947.

This invention has for its object to provide a construction in carburetors by which is accomplished a desired control of the fuel mixture. For this purpose I provide means whereby the position of a fuel throttling element in the fuel nozzle is controlled by the differences of pressure existing on opposite sides of the usual air throttle and in which, in addition to or apart from the above, the area of an air choke adjacent to the nozzle is, above a specified demand for air by the engine, controlled by such pressure differences. My invention further consists in the construction, arrangement and combination of the several parts as will be hereinafter more fully described and claimed.

Referring to the accompanying drawings in which corresponding parts are designated by corresponding marks of reference:

20. Figure 1 is a vertical section partly in elevation of a carburetor embodying my invention.

Figure 2 is a vertical section of parts shown in Figure 1 with the casing removed.

Figure 3 is a view similar to Figure 2, but 25 on an enlarged scale and with certain parts broken away.

Figure 4 is a plan view of the fuel nozzle and.

Figure 5 is a side elevation thereof.

30. Figure 6 is a side view of the air choke sleeve and its associated weight.

Figure 7 is a plan view of the parts shown in Figure 6.

Figure 8 is a detail representing the manner of mounting of the metering pin.

Referring to the drawings, 1 represents a suitable carburetor casing, forming a mixing chamber, having mounted near its upper end, which is to be connected to the manifold of the engine, the throttle 2 in the form of a butterfly and having about midway of its height a restriction forming a stop for the member 20 to be hereinafter described, and preferably forming the seat 3 of an air valve, 45 to be hereafter described. The mixing chamber casing below the seat 3 is connected to an air intake 4, having the usual choke 5 therein, the bottom of the casing being provided with a fuel intake 6 which leads from 50 the usual float chamber 7 to a gasoline nozzle

8. This nozzle enters and extends up through the lower part of the mixing chamber casing. The nozzle passes through a suitable packing box 9 formed on the bottom of the casing, and through an upward extension 10 fastened to such bottom, it being threaded into the latter for adjustment. Within the nozzle is threaded the stem of metering pin 13, having a conical head 14 normally terminating below the top of the nozzle. In order to preserve alignment of the head on adjustment, the threaded stem is connected by a ball-and-socket joint shown at 15 in Figure 3 with the conical head of the pin.

The upper end of the extension 10 which is 65 annular, terminates slightly below the nozzle 8, and forms the seat for an air choke sleeve, it having notches 16 in its upper outer edges to pass a limited quantity of air at all times.

Within the upper part of the mixing chamber is contained a member 20 shown as consisting of two cylindrical parts, the upper one, 20a, being of greater diameter than the lower one, 20b, and the two being united by a tapering portion 20c which cooperates with 75 and seats upon the seat 3 in the mixing chamber. The upper portion of this member 20 is hollow and forms a cylinder whose function will be described later. The member 20 is guided for movement by having its lower portion 20b entering the upper end of a perforated shield 24 which rises from the base of the carburetor and surrounds the fuel nozzle and the extension 10, being spaced somewhat therefrom. Also for the purpose of 80 guiding the member 20 its upper end receives a piston head 21 fast on a tubular guide 22, whose upper end is sleeved on the throttle shaft 23, the guide extending through the upper head 25 of the member 20. The air 85 passage 26 within the tube has its upper end communicating with the space above the throttle, such communication being controlled by a ball check valve 27. The head 25 of the member 20 is threaded onto the circumferential walls thereof to permit the assemblage within the member of desired parts, a spring 30 being interposed between such head and the piston head. This spring serves 90 to carry the weight of the member 20 and 95

100

parts mounted thereon, and when the engine is not running, maintains the member slightly off the seat 3. The space between the head 25 and the piston head is in communication with the bore 26 of the tubular guide through a port 31 of restricted diameter in the wall of the guide.

An annular shoulder 32 is formed within the upper cavity of the member 20 and is threaded to receive the plug 33 which forms the lower head for the cylinder in which the piston head 21 is contained. The plug has an annular flange 34 on its upper face, within which is received a second piston head 35 on the upper tubular end of a piston 36, the lower end of which terminates in a tube 36a which enters the upper end of the nozzle, and at about the level of the end of the nozzle is tapered. The upper tubular end of the piston 36 receives the lower end of the tubular guide 22 through a suitable self-centering packing box. This self-centering packing box may consist of a washer 37 snugly surrounding the tubular guide 22 and held within a cavity 38 in the top of the piston 36. The interior cavity at the top of the piston 35 communicates with the central bore 26 of the guide and through ports α with the space below the piston head 35, so that in such last named space also exists the same pressure as exists in the manifold. The annular shoulder 32 has ports 40 therein communicating with the space within the base of the enlarged portion 21 of the member 20 and such space communicates with the space exterior of the member through peripheral ports 41, so that while manifold pressure exists in the space above the piston head 21 and below the piston head 34, the space between the piston heads has mixing chamber pressure within it. Hence the member 20 moves up and down as a whole in response to the variation of differences of pressure in the mixing chamber and the manifold and the metering tube moves up and down in respect to the member 20 in response to the same variation of pressure, a spring 60 normally lifting the piston head to its upper limit of movement.

A shoulder 42 is formed on the interior of the member 20 at about the upper end of the lower portion thereof, and serves as a support for the annular weight 43 for the air choke sleeve and which has a corresponding engaging shoulder 44, by which such weight member is carried in the member 20.

The lower end of the weight surrounds the upper reduced end of the annular air choke sleeve 45, the bottom of which is interiorly tapered and surrounds and cooperates with the upper end of the primary air valve seat formed on the top of the extension 10. The sleeve 45 thus surrounds the tube 36a which enters the fuel nozzle and which has perforations 36b therein by which fuel may be drawn up from the nozzle into the interior of the

sleeve, where it is mixed with air which has passed the air choke, and which passes through the central bore of the weight 43 to the peripheral ports 41.

In order to prevent this passage being closed at such times as the weight member 43 is lifted from its seat by the sleeve, the former has its upper end notched as at 47.

The general operation is as follows:

When the engine is not running, the parts are in the position shown in Figures 1 and 2, that is to say, the member 20c is slightly off the seat 3 and has lifted the weight 43 off the air choke sleeve which is resting on the fuel nozzle 10. The secondary piston 35 is held raised within the member 20 by its spring 60.

If the engine is running idle with the throttle more or less closed, the differences in pressure existing in the manifold and in the mixing chamber below the throttle will, by the excess of the latter pressure over the former, depress the secondary piston and lower the tube 36a with a consequent reduction in the fuel flow area between it and the nozzle 8, fuel being aspirated through such area by the air passing through the notches 16 in the edge of the fuel nozzle. The pressure difference also causes the member 20 to descend and seat on the seat 3 but the weight 43 will not be at this time in contact with or rest on the air choke sleeve. As the engine increases its demand for air, the air drawn up through the notches 16, will drag with it the air choke sleeve, increasing the flow area for the air. At sometime in its movement, this sleeve will contact with its weight 43 and its movement will then be dependent not only on its own weight but on the mass of the weight.

Upon a further opening of the throttle to increase the engine speed the pressures on the two sides of the butterfly tend to equalize so that the spring 30 is enabled to lift the member 20, thereby unseating the member from the seat 3 and at the same time lifting the weight 43, this enabling the choke sleeve to resume its free movement until again retarded by the weight.

The differences of pressure may still be sufficient to compress the spring 60 and to hold the secondary piston 36 down. As the throttle is still further opened with the consequent greater equalization of pressure on both sides of it, the spring 60 comes into action to lift the secondary piston 36 and in consequence to increase the fuel flow area around the tapered end 36a of that piston. On a reverse actuation of the throttle the reverse movements occur.

In order to retard the movements of the member 20 and the secondary piston 36, and to prevent an abrupt change in fuel condition before the engine has had an opportunity to respond to the change in position of the throttle, the check valve 27 is employed.

Upon the opening of the throttle there immediately results an abrupt decrease in the vacuum (increase of pressure) in the manifold with an increase of vacuum (decrease of pressure) in the mixing chamber. Upon the increase of pressure in the manifold over that existing between the two piston heads 21 and 35, the ball 27 will seat, trapping above the piston head 21, and below the piston head 10 35 gases under the pressure which had existed in the manifold prior to the opening of the throttle and hence more or less nearly equal to the new condition of pressure existing in the mixing chamber. Hence the elements above described, which depend for their action upon the pressure differences, are for the time being rendered inert and this inert condition will continue until leakage restores them to their previous relative condition of pressure. In order to prolong this period, without making such close fits as would induce friction, I may, as shown in Figure 1, provide a vacuum chamber 66 exterior of the carburetor but connected to the 20 central bore 26 of the guide 22 through the central bore 67 in the shaft 23 of the butterfly.

As a convenient and efficient device for manually varying the fuel supply, the metering pin 14 is employed. By lowering this pin so that its tapered head becomes opposite the lower end of the tubular base of the piston 36a the supply of fuel to the interior of such piston may be controlled and hence the 30 flow of fuel from the ports 36b in such piston under the pull of the air flowing through the air choke sleeve may also be controlled.

Having thus described my invention what I claim is:—

40 1. In a carburetor the combination of a mixing chamber, a fuel nozzle therein, a throttle near the exit end of the mixing chamber, an air choke sleeve adjacent to the nozzle and an air valve whose position is determined by the differences of pressure on opposite sides of the throttle and which controls the area of the air choke and also the area of an air passage in the mixing chamber but remote from the nozzle.

50 2. In a carburetor the combination of a mixing chamber, a fuel nozzle therein, a throttle near the exit end of the chamber, an air choke sleeve surrounding the nozzle and restricted in its movement by a yielding abutment and means actuated by difference of pressure on opposite sides of the throttle for controlling the position of the abutment.

60 3. In a carburetor the combination of a mixing chamber, a fuel nozzle therein, a throttle near the exit end of the chamber, an air choke sleeve surrounding the nozzle and movable under the flow of air through the same, a yielding member restricting the movement of the choke sleeve and means actuated by difference of pressure on opposite

sides of the throttle for controlling the position of the yielding member.

4. In a carburetor, the combination of a mixing chamber, a fuel nozzle therein, a throttle near the exit end of the chamber, an 70 element throttling the nozzle, a cylinder, a piston head shiftable therein by the pressure differences above and below the throttle and controlling the movement of the fuel throttle, and means controlled by the pressures above 75 and below the throttle for shifting the cylinder and piston head therein.

5. In a carburetor, the combination of a mixing chamber, a fuel nozzle therein, a throttle near the exit end of the chamber, an 80 element throttling the nozzle, a cylinder, a piston head shiftable therein by the pressure differences above and below the throttle and controlling the movement of the fuel throttling element, means controlled by the pressures above and below the throttle for shifting the cylinder and piston head therein, an air choke sleeve surrounding the nozzle and means actuated by the cylinder for controlling the movement of the air choke sleeve. 85

6. In a carburetor the combination of a mixing chamber, a fuel nozzle therein, a throttle near the exit end of the chamber, a double headed cylinder in the mixing chamber, a fixed piston head near one end of the 90 cylinder, a movable piston head near the opposite end of the cylinder, the space between the pistons communicating with the mixing chamber below the throttle and the spaces between each piston and the adjacent end of the 95 cylinder communicating with the space above the throttle and a throttling element for the fuel controlled by the movable piston head.

7. In a carburetor the combination of a mixing chamber, a fuel nozzle therein, a 105 throttle near the exit end of the chamber, a double headed cylinder in the mixing chamber, a fixed piston head near one end of the cylinder, a movable piston head near the opposite end of the cylinder, the space between the pistons communicating with the mixing chamber below the throttle and the spaces between each piston and the adjacent end of the cylinder communicating with the space above the throttle, a throttling element for the fuel controlled by the movable piston head, and an air choke sleeve surrounding the nozzle and controlled by the movement of the cylinder. 110

8. In a carburetor, the combination of a 120 mixing chamber, a fuel nozzle therein, a throttle near the exit end of the cylinder, a double headed cylinder and a piston contained in the mixing chamber, one of the said elements being fixed and the other movable, a second piston head in the movable element, the space between the second piston head and the fixed element communicating with the mixing chamber below the throttle and the space between the first piston head and the 125 130

cylinder and between the second piston head and the moving element communicating with the space above the throttle and a metering element controlled by the second piston head.

- 5 9. In a carburetor, the combination of a mixing chamber, a fuel nozzle therein, a throttle near the exit end of the cylinder, a double headed cylinder and a piston head contained in the mixing chamber, one of the
10 said elements being fixed and the other movable, a second piston head in the movable element, the space between the second piston head and the fixed element communicating with the mixing chamber below the throttle and the space between the first piston head and the cylinder and between the second piston head and the moving element communicating with the space above the throttle, a metering element controlled by the second
15 piston head, and an air choke controlled by the movement of the cylinder.

10. In a carburetor the combination with a mixing chamber, a fuel nozzle therein, a throttle near the exit end of the chamber, a
20 cylinder within the chamber, a piston head within the cylinder, one of the last two elements being movable, the space within the cylinder being in communication with the space above the throttle, a check valve controlling such communication, means for controlling fuel mixture controlled by the movement of the movable element, and a vacuum reservoir exterior of the carburetor and connected with the space within the cylinder.

- 25 35. In testimony whereof I hereunto affix my signature.
